UNITED STATES PATENT OFFICE.

WILLIAM KEFFER, OF PHILADELPHIA, PENNSYLVANIA.

CROSSING.

1,072,855.

Specification of Letters Patent.

Patented Sept. 9, 1913.

Application filed May 15, 1913. Serial No. 767,810.

To all whom it may concern:

Be it known that I, WILLIAM KEFFER, a citizen of the United States, residing at Philadelphia, in the county of Philadelphia and State of Pennsylvania, have invented certain new and useful Improvements in Crossings, of which the following is a specification.

My invention relates to improvements in crossings, and more particularly to an improved device for securing the boards or timbers between the rails, so as to prevent any possibility of the timbers being drawn upwardly by the suction of a passing train.

15 A further object is to provide improvements of this character which are simple and inexpensive in construction, but strong and durable in use.

With these and other objects in view, the invention consists in certain novel features of construction and combinations and arrangements of parts as will be more fully hereinafter described and pointed out in the claims.

25 In the accompanying drawings: Figure 1 is a plan view illustrating my improvements. Fig. 2 is a view in longitudinal section on the line 2—2 of Fig. 1, and Fig. 3 is a view in cross section on the line 3—3 of Fig. 1.

1, 1, represent the rails and 2 are the timbers or planks secured to the ties 3 by nails or spikes 4. At one end of the timbers, namely at the end thereof which is first reached by the train, my improved device is located, and consists of a metal plate 5 which is secured at one edge over the timbers 2 by means of nails or spikes 4. The other edge of plate 5 is bent downwardly and confined between 50 metal strips 6 and 7, the former having its ends positioned over the base flanges of the rails 1, and the latter extended under the rails, so that any suction of the train cannot possibly pull the timbers 2 away from the ties when the parts are secured together. Strips 6 and 7, and plate 5 have registering openings for the reception of bolts 8 which are secured in place by nuts 9 to effectually clamp the parts together, yet permit a ready assem-

blage of the strips above and below the plate 5 and in proper engagement with the base flanges of the rails.

When the crossing is of a length to require more than one section of plank or timber 2, the adjacent ends of the timbers or planks are rabbed as shown at 10, and it is to be understood that the overlying tongues will be upon the sections nearest plate 5, so that the suction of the train will be resisted by the overlapping or overlying connection.

Various slight changes might be made in the general form and arrangement of parts described without departing from my invention, and hence I do not limit myself to the precise details set forth, but consider myself at liberty to make such changes and alterations as fairly fall within the spirit and scope of the appended claims.

Having thus described my invention, what I claim as new and desire to secure by Letters Patent is:

1. A crossing comprising timbers positioned between the rails, a plate secured at 75 one edge upon the said timbers, and a strip secured to said plate and at its ends projected under the rails, substantially as described.

2. A crossing comprising a plurality of 80 timbers secured to the ties between the rails, a metal plate having one edge positioned upon and secured to the end of the timbers in the direction of the train's approach, and strips secured to the plate at its other edge 85 and engaging respectively above and below the base flanges of the rails, substantially as described.

3. A crossing comprising a plurality of 90 timbers secured to the ties between the rails, a metal plate having one edge positioned upon and secured to the end of the timbers in the direction of the train's approach, strips secured to the plate at its other edge 95 and engaging respectively above and below the base flanges of the rails, said strips and said plates having registering openings, bolts in said openings, and nuts secured to said bolt and clamping the strips and plate together, substantially as described.

4. A crossing comprising a plurality of timbers secured to the ties between the rails, a metal plate having one edge positioned upon and secured to the end of the timbers in the direction of the train's approach, strips secured to the plate at its other edge and engaging respectively above and below the base flanges of the rails, and said timbers comprising a plurality of sections hav-

ing tongue and groove engagement at their 10 ends, substantially as described.

In testimony whereof I have signed my name to this specification in the presence of two subscribing witnesses.

WILLIAM KEFFER.
